SUPPORT HOUSING FOR ELECTRONIC ALARM UNIT

James F. Pinkham, Kensington, Md., assignor to
Multra-Guard, Inc., Rockville, Md.

Filed Feb. 5, 1970, Ser. No. 21,294

Term of patent 14 years

Int. Cl. D29—99

U.S. Cl. D72—1

FIG1

FIG2

FIG3

FIG4

FIG5

FIG. 1 is a front elevational view of a support housing for electronic alarm unit showing my new design;

FIG. 2 is a rear elevational view thereof;

FIG. 3 is a top plan view thereof, the bottom being substantially plain;

FIG. 4 is a side elevational view thereof; and

FIG. 5 is an elevational view of the opposite side from that shown in FIG. 4.

The indicia in FIG. 1 and the alarm unit body in FIGS. 2 through 5 are shown in broken lines for illustrative purposes only.

I claim:

The ornamental design for a support housing for electronic alarm unit, substantially as shown and described.
